UNITED STATES PATENT OFFICE.

ALFRED JEAN GALLAND, OF PARIS, FRANCE.

BOTTLE-FILLING APPARATUS.

Application filed June 2, 1925, Serial No. 34,457, and in France July 9, 1924.

The present invention relates to filling apparatus for bottles, flagons and similar receivers so that the said receivers can be wholly or partly filled with liquid. This apparatus allows the filling to be stopped automatically when the liquid has attained in the receiver a predetermined height, the level of which is decided by a preliminary and variable adjustment.

This apparatus is of the kind comprising a supporting plate for the bottle or other receiver, a lever controlled cock for the supply of liquid, and a filling tube with a stopper or plug for the receiver and with an air escape passage, the supporting plate being normally brought back towards the filling tube by a suitable spring.

In the present apparatus, the inlet-aperture of the air-escape passage is fast with the plunger filling-tube and is situated near the orifice of this tube and preferably at the height or level of said orifice. A ring supporting a tight joint, of rubber for example, for the sealing or closing of the receiver by pressure upon the neck, can be slid along the plunger tube and is furnished with a stop member, a pressure screw or ring for example, in such a way that by regulating the position of this ring upon the filling tube, the operator can determine as desired and in a variable manner, the depth of entry of this filling tube into the receiver and therefore the height of the inlet-aperture of the air-escape passage relatively to this receiver, such height determining the maximum level for filling. A tappet or striking piece is actuated by the support for the receiver by means of suitable intermediate mechanism and in such a way that when the said support is not occupied by a receiver, this tappet or striking piece blocks or closes the bore of the cock through which the liquid arrives, the lowering of the support for the positioning of the bottle or other receiver thereon, being so designed as to actuate this tappet or striking piece in such a way as to unblock or free the cock, which arrangement thus prevents any accidental manipulation of the cock before the positioning of the bottle or other receiver upon the support.

Upon the annexed drawing I have illustrated one form of carrying out the present invention. Figure 1 shows in perspective a front view of the apparatus mounted on a table. Figures 2 and 3 are views respectively of the rear, the other in side view of

part of the apparatus, showing the frame, the support for the receiver to be filled, sliding rods and the blocking tappet or striking piece. Figure 4 shows in elevation, in part section and on a larger scale, the cock mounted between the filling tube and the union for the liquid-supply tube. Figure 5 is an end view of the filling tube showing also the air escape pipe.

The base *a* of a framework *b* which forms a pedestal or upright, rests upon a table *x* which it presses, in the manner of a vise, between itself and the end of a screw *c*, which latter is screwed through the elbowed extremity *a*² of a tailpiece *a*¹ which is fast with the base *a*. In other words, the frame *b* is clamped to the table *x* by means of the clamping screw *c*.

The frame *b* is provided with a longitudinal slot or recess *b*¹ in which can slide the rear portion of the cock *d* so that the height of the latter can be adjusted, particularly when using bottles or receivers of different heights (Figure 1 and 4). The cock *d* is held against the frame *b* by means of the flanged member *d*¹ mounted on the barrel of the cock *d* and a locking nut *d*² (see Figure 4).

The rotary valve *d*³ or devices for closing and opening the bore of the cock the details of which form no part of the invention are located in the box *d*¹ and are made fast with the spindle which passes through this box and through a suitable gland or stuffing box. A lever *e* which is mounted on the said spindle so as to turn the latter, is actuated by means of a pedal *e*¹ to which it is connected by an adjustable rod *e*². The spindle which controls the valve or closing and opening devices of the cock *d* is normally brought to the closed position of said cock by means of a spring *e*³.

The cock *d* and the filling tube or pipe *f* are provided at their facing ends with the members of a conical seating, the one *d*³ being a male cone and the other *f*¹ a female cone, and they are assembled together in fluid-tight fashion by pressure together of these two parts by means of a union *d*⁴ screw-threaded for that purpose.

A passage *h* for the escape of air, and shown in the form of an inner pipe, is so arranged that its lower aperture is at the same level as that of the filling tube *f*. The arrangement of the pipe *h* inside the tube *f* is clearly shown in Figures 4 and 5 and it will be noted that the inlet aperture for the escape

of air from the bottle is at the same level as the discharge outlet for the liquid from the tube h .

At its upper end, the passage or pipe h 5 communicates with a small port h^1 formed in the thickness of the upper part of the filling tube f . The screw-threaded end of the port h^1 is provided with a junction piece h^2 (Figure 4) to which is connected a flexible pipe h^3 (Figure 1), of which the other end delivers into a receiver z .

A split ring i , screw-threaded exteriorly, is made fast with a plate i^1 which presses the rubber or other washer i^2 upon the neck 15 of the bottle y to close it, and is locked and fixed in the desired position upon the filling tube f by means of a locking ring i^3 which screws upon the threaded portion of the ring i , these two parts entering into engagement 20 at their upper portions by means of two corresponding conical faces i^4 and i^5 .

The platform support j for the bottle y or other receiver is so mounted as to be capable of sliding up and down relatively to 25 the frame b by means of two rods j^1 which at their bases pass through two sockets j^4 secured to the arm j^5 shown bolted to this platform support j . The rods j^1 are adjustable as to height in the sockets j^4 by 30 means of wing-fitted locking screws j^6 . The rods j^1 slide in bosses or lugs b^2 formed with or provided upon the frame b . The platform support j is brought back into its upper position by means of two springs j^2 fixed 35 at one end to the hooks j^7 (Figures 2 and 3) fast with the frame b , and at the other end to the hooks j^8 fast with the sockets j^4 .

A counterweight j^9 , made hollow so that it can be supplied with the required weight 40 of metal or the like, is caused to balance the variable weight of the bottle y by means of its action upon the cable j^9 passing over the pulley j^{10} and connected to a hook j^{11} supported by a rod j^{12} screwed into the base 45 of the plate support j . The spindle of the pulley j^{10} is supported by the neck a^1 which projects from the base a of the frame b .

Upon one of the rods j^1 is mounted, so 50 as to slide therewith, a striking piece l and this striking piece is set at the desired position on rod j^1 by a locking screw l^1 . This striking piece l passes through a lateral slot b^3 in the frame b and has bolted upon it a tappet or contact member l^2 . The striking piece l is locked on the rod j^1 at a variable height corresponding with the position of the cock d upon the frame b in such a way that when the support j and the rods 60 j^1 are in the upper position, that is to say before the placing of the bottle y upon the platform support j , the contact member l^2 locates itself immediately beneath the lever e for operating the cock, thus blocking this lever and preventing any accidental opening 65 of the rotary plug d^9 of the cock d . Con-

versely, when the bottle y is put upon the support j (see Figure 1), the contact member l^2 following the descent of the rods j^1 , moves away from and frees the lever e of the cock d . The striking piece l will thus 70 automatically and alternately take up its blocking position and be removed therefrom during the working of the apparatus.

The platform support j is actuated by means of a pedal k to which it is connected 75 by a chain k^1 .

At its rear (Figure 4), the cock d is provided with a union d^5 and a tube d^6 furnished with a draw-off cock d^8 , and this tube d^6 is exteriorly undulated so as to engage 80 with a flexible supply pipe d^7 (Figure 1) conveying liquid from a vat or storage vessel Z .

Liquid from the vat Z is thus constantly supplied to the cock d and when the latter is 85 opened, such liquid passes into the filling pipe f and bottle y . Air escaping from the bottle y passes out through the pipe h . When the level of liquid in the bottle y reaches the bottom of the pipes f and h , no 90 more air from the bottle will be expelled up the pipe h . As above mentioned, the filling tube descends into the bottle y to a depth determined by the rubber plug or sealing member i^2 and that member can be set 95 at any desired position along the height of the filling tube f .

What I claim is:—

1. An apparatus for filling bottles, flagons and similar containers, comprising a support 100 for the container, a liquid supply cock with control lever, a filling tube with a lower aperture, a sealing member for the container and an air escape passage with a lower aperture, a spring device whereby the container-support is normally brought towards the filling tube, the lower aperture to the air escape passage being arranged adjacent to the lower aperture of the filling tube and at the same level as the second said lower 105 aperture, the sealing member for the container being adjustable in position along the said filling tube, means for locking said sealing member in the desired position upon said tube, a contact member, and means for 110 adjustably connecting said member to the support, the said contact member being adjusted so as to lock the control-lever for the cock in its closed position, when the support is in its position nearest to the filling tube and to release the said lever when the support is moved away into the filling position.

2. Apparatus for supplying liquid to containers, comprising an upright frame, lugs 125 thereon, means for supporting said frame, a cock, means for adjustably mounting said cock in said frame, means for supplying the liquid to said cock, a lever controlling the opening and closing of the bore of said cock, 130

a filling tube connected to said cock, an air escape pipe arranged within said filling tube, said air escape pipe having its lower end level with the lower end of the filling tube 5 and its upper end connected with a lateral outlet for the escaping air, a spring-suspended platform support for the container, guiding tubes connected with said container-support and passing through the lugs upon 10 said upright frame, means for depressing said container support against the action of its spring suspension, and a striking piece adjustably mounted on one of said guiding tubes, said striking piece adapted to engage and block the said cock-controlling lever when the tubes and container support are 15 in their upper position so that the cock cannot be accidentally opened.

3. Apparatus for supplying liquid to containers, comprising an upright frame, lugs thereon, means for supporting said frame, a cock, means for adjustably mounting said cock in said frame in such a manner as to pass through said frame, means for supplying the liquid to said cock, a lever controlling the opening and closing of the bore of 25 said cock, a filling tube detachably connected to said cock, an air escape pipe arranged in side said filling tube, said air escape pipe having its lower end level with the lower end 30 of the filling tube and its upper end connected with a lateral outlet for the escaping air, a spring-suspended platform support for the container, guiding tubes connected with said container-support and passing through 35 the lugs upon said upright frame, means for depressing said platform-support against the action of its spring suspension, a striking piece adjustably mounted on one of said guiding tubes, said striking piece adapted to 40 engage and block the said cock-controlling lever when the tubes and platform-support are in their upper position so that the cock cannot be accidentally opened, a sealing member mounted on the exterior of the filling tube, said sealing member having a plate 45 provided with yielding material being adapted to close the mouth of the container and said sealing member being adjustable as to position along said filling tube, and means 50 for locking said sealing member in the desired position upon said filling tube.

In witness whereof I have hereunto affixed my signature.

ALFRED JEAN GALLAND.
